(57) **CLAIM**

The ornamental design for a vehicle LED light, as shown and described.

DESCRIPTION

FIG. 1 is a perspective view of the vehicle LED light;

FIG. 2 is a front view thereof;

FIG. 3 is a rear view thereof;

FIG. 4 is a bottom view thereof;

FIG. 5 is a top view thereof;

FIG. 6 is a left-side view thereof; and,

FIG. 7 is a right-side view thereof.

The broken lines in the drawings depict portions of the vehicle LED light that form no part of the claimed design.
